(57) **CLAIM**

The ornamental design for a display screen with animated graphical user interface as shown and described.

DESCRIPTION

FIG. 1 is a front view of a first image in a sequence for a display screen with animated graphical user interface according to a first embodiment of the present disclosure. FIG. 2 is a front view of a second image thereof.

FIG. 3 is a front view of a third image thereof.

FIG. 4 is a front view of a fourth image thereof.

FIG. 5 is a front view of a first image in a sequence for a display screen with animated graphical user interface according to a second embodiment of the present disclosure. FIG. 6 is a front view of a second image thereof.

FIG. 7 is a front view of a third image thereof; and, FIG. 8 is a front view of a fourth image thereof.

The outer broken lines in the Figures show a display screen and form no part of the claimed design. All thin unevenly broken lines and all other broken lines in the Figures show portions of the animated graphical user interface that form no part of the claimed design.

The appearance of the transitional image sequentially transitions between the images shown in FIGS. 1-4 and FIGS. 5-8. The process or period in which one image transitions to another image forms no part of the claimed design.

1 Claim, 8 Drawing Sheets
